I claim the ornamental design for a magnifier and lamp stand, as shown and described.

DESCRIPTION

FIG. 1 is a front perspective view of a magnifier and lamp stand according to my new design;

FIG. 2 is a rear perspective view thereof;

FIG. 3 is a front view thereof;

FIG. 4 is a rear view thereof;

FIG. 5 is a top view thereof;

FIG. 6 is a right side view thereof;

FIG. 7 is a left side view thereof; and,

FIG. 8 is a bottom view thereof.

The broken lines showing a base of the magnifier and lamp stand is for the purpose of illustrating a base and forms no part of the claimed design.
